Primary Examiner — Celia Murphy*Assistant Examiner* — Clare Ann Gannon(74) *Attorney, Agent, or Firm* — Donald J. Ranft; Collen IP(57) **CLAIM**

The ornamental design for a sandal, as shown.

DESCRIPTION

FIG. 1 is a top right perspective view of a sandal showing my new design;

FIG. 2 is a top left perspective view thereof;

FIG. 3 is a bottom right perspective view thereof;

FIG. 4 is a bottom left perspective view thereof;

FIG. 5 is a top view thereof;

FIG. 6 is a bottom view thereof;

FIG. 7 is a left side view thereof;

FIG. 8 is a right side view thereof;

FIG. 9 is a front view thereof; and,

FIG. 10 is a rear view thereof.

The portions of the sandal shown in broken lines represent thread stitching.
